UNITED STATES PATENT OFFICE.

ROBERT J. SMYTH AND FRANK ALLINGER, OF YERMO, CALIFORNIA.

HYDROCARBON-BURNER.

No. 926,218.

Specification of Letters Patent.

Patented June 29, 1909.

Application filed September 25, 1908. Serial No. 454,743.

To all whom it may concern:

Be it known that we, ROBERT J. SMYTH, a citizen of Canada, and FRANK ALLINGER, a citizen of the United States, both residing at Yermo, in the county of San Bernardino and State of California, have invented new and useful Improvements in Hydrocarbon-Burners, of which the following is a specification.

This invention relates to a hydro-carbon burner of the injector type and the object thereof is to provide a burner which will thoroughly atomize and mix the constituents of the fuel so that they may be burned efficiently and uniformly without smoking and without leaving a deposit of solid matter.

The invention consists in an arrangement whereby both steam and air are thoroughly mixed with hydrocarbons before they are discharged, from the burner tip. The orifice in the burner tip is of a considerable less diameter than the mixing tube which feeds the fuel to the said burner tip, which is formed of a gradual tapering point in such manner as to produce a back pressure in the supply pipe.

In the accompanying drawings, forming a part of this specification:—Figure 1,— is a vertical longitudinal section of the burner. Fig. 2,— is an enlarged cross-section taken on line 2—2 of Fig. 1.

In the drawings 5 designates the body of the burner which is chambered as at 6 and connected to oil supply pipe 7 which is controlled by valve 8. A nozzle 9 of double cone shape is screwed into the lower end of body 5 this nozzle being of sufficient capacity to discharge the maximum amount of fuel required of the burner. A pipe 10 connects with the outer end of nozzle 9 and ends in a burner tip 11 which may be at any convenient distance from the burner itself. Within body 5 a nozzle 12 is arranged projecting through chamber 6 and discharging into nozzle 9. The upper end of nozzle 12 connects with a chamber 13 formed in body 5, this chamber also being connected by ports 14 to the atmosphere. Projecting into chamber 13 is a steam nozzle 15 which is supplied with steam through a pipe 16 controlled by valve 17.

In the operation of this burner an appropriate volume of steam is admitted to nozzle 15 and is discharged therefrom directly into nozzle 12, drawing atmospheric air with it

through nozzle 12 from ports 14. The mixed volume of steam and air passing through 12 is again discharged expansively into nozzle 9 and oil from pipe 7 is drawn through the nozzle in a volume regulated by valve 8. The volume of oil, steam and air discharged from nozzle 9 into pipe 10 is thoroughly mixed and atomized on account of the velocity of the steam issuing from nozzle 15 and produces in the pipe 10 considerable pressure on account of this velocity and the condensation of the steam. This pressure enables the fuel to be led to points quite a distance from the burner instead of being necessarily discharged from the burner tip immediately adjacent the burner. On this account the burner may be placed away from the flame so that it is possessed of a much longer life than the average burner not being subjected to the intense heat of immediate exposure to the flames. Being conveniently removed from the immediate vicinity of the flame one burner may suffice for feeding a pair of furnaces thus reducing expense for both installation and maintenance.

We claim:

1. In a hydrocarbon burner the combination of a body portion, a steam pipe terminating in a nozzle in said body portion, said body portion being formed with air ports adapted to admit air above the terminal point of said nozzle, a second nozzle in said body portion, said nozzles having bores of substantially the same diameter, an oil inlet adapted to admit oil above the termination of said second nozzle, and a third nozzle by means of which the mixture of steam, air and oil are ejected, to a burner tip.

2. In a hydrocarbon burner in combination, a body portion, a steam nozzle, means to admit air around said steam nozzle, means to admit oil into said body portion, means to conduct said mixture of steam and air beyond the said oil admission means, means so formed as to mix the oil with said mixture of steam and air, and means to deliver said mixture of steam, air and oil to a burner tip, said burner tip being formed of a curved tube, having a tapering tip and being swiveled to the mixing chamber.

3. In a hydrocarbon burner, in combination, a body portion, means to admit steam to said body portion, aspirating means adapted to use said steam to draw air into

said body portion, a second aspirating means adapted to use the mixture of steam and air, to draw oil into said body portion, said aspirating means comprising nozzles having 5 bores of substantially the same diameter, and means to deliver said mixture of steam, air and oil to a burner tip.

In witness that we claim the foregoing we

have hereunto subscribed our names this 8th day of September, 1908.

ROBERT J. SMYTH.
FRANK ALLINGER.
